US00D643060S

(12) **United States Design Patent**
Clegg et al.

(10) **Patent No.:** US D643,060 S
(45) **Date of Patent:** ** Aug. 9, 2011

(54) **VIDEO INSERT**

(75) Inventors: **Timothy P. Clegg**, Manhattan Beach, CA (US); **Michael D. Ronk**, Lawndale, CA (US)

(73) Assignee: **Americhip, Inc.**, Los Angeles, CA (US)

(**) Term: **14 Years**

(21) Appl. No.: **29/385,685**

(22) Filed: **Feb. 17, 2011**
